PORTABLE DICTATING MACHINE

Gerhard Dietrich, Nuremberg, Germany, assignor to
Grundig E.M.V. Elektro-Mechanische-Versuchs-Anstalt
Max Grundig, Furth, Germany

Filed June 21, 1973, Ser. No. 372,409

Term of patent 14 years

Int. Cl. D14—02
U.S. Cl. D26—14 B

FIG. 1

FIG. 2

FIG. 3

FIG. 4

FIG. 5

FIG. 6

FIG. 7

FIG. 1 is a perspective view of a portable dictating machine showing my new design;

FIG. 2 is a front view of the portable dictating machine shown in FIG. 1;

FIG. 3 is a rear view of the portable dictating machine shown in FIG. 1;

FIG. 4 is a bottom view of the portable dictating machine shown in FIG. 1;

FIG. 5 is a top plan view of the portable dictating machine shown in FIG. 1;

FIG. 6 is a side view of the portable dictating machine shown in FIG. 1; and

FIG. 7 is an opposite side view of the portable machine shown in FIG. 1.

I claim:

The ornamental design for a portable dictating machine, substantially as shown.
